CLAIM

The ornamental design for a cylindrical battery, as shown and described.

DESCRIPTION

FIG. 1 is a perspective view of a cylindrical battery according to the present design;

FIG. 2 is another perspective view of the cylindrical battery according to the present design;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line in the drawing depict portions of the cylindrical battery that form no part of the claimed design. In FIGS. 1 and 3, the oblique line shading depicts the transparent surface of a feature of the cylindrical battery.
